THERMOSTATIC FUEL CONTROL SYSTEM

Filed April 21, 1928

UNITED STATES PATENT OFFICE

EDMUND J. TE PAS, OF LAKWOOD, OHIO, ASSIGNOR TO THE PATROL VALVE COMPANY,
OF CLEVELAND, OHIO, A CORPORATION OF OHIO

THERMOSTATIC FUEL CONTROL SYSTEM

Application filed April 21, 1928. Serial No. 271,804.

This invention relates to gas fired liquid air which is drawn into the mixing tube usually heaters and in particular the gas burner contains dust and other foreign matter which in time clogs up the pores or openings

in the gauze and eventually closes the passages between the burner orifices and the gas 55

and air mixing tube. This condition is as hazardous as the condition which the application of the gauze or screen was intended to correct, and may result in the escape of unburned gas that might cause an explosion or a case of asphyxiation. 60

On account of the above characteristics of the aforementioned type of burner, the use of a graduating thermostat with this type of burner is objectionable and a thermostat having a snap acting valve is now generally used in this connection and for this purpose. By the use of a snap acting valve the gas burner is either operating at full capacity or the gas supply is entirely shut off thereto. 65

This arrangement allows the use of a gauzeless burner and practically eliminates the tendency these burners have to flash back and burn in their mixing tube. While the above arrangement eliminates a great many 70 of the difficulties encountered in the operation of the Bunsen type gas burner at the same time it necessitates the use of a more complicated thermostatic valve, which materially increases the cost of the appliance with which 75 it is used and at the same time by reason of the increased number of operating parts is more apt to get out of order than a control which uses a simple graduating thermostat. 80

The second type of control above referred 85 to, wherein the independent pilot light is dispensed with and the main burner is in operation at all times; considerably simplifies the control but it is objectionable in that at certain times in the operation of burners of 90 this type the burner operates with a yellow flame which is apt to produce considerable amount of soot or carbon.

Another objection to both of the above 95 named control systems is the possibility of extinguishment of either the pilot light or the reduced flame of the main burner. In the happening of such an event, the thermostatic valve may again turn on the supply of gas to the main burner and as there is no 100

5 liquid heaters of the type referred to in this application by means of a thermostatic valve in contact with the liquid which is being heated. The thermostatic valve automatically controls the fuel supply to the heating 10 burner which is used in connection with the appliance. Appliances of this type are in some cases provided with a constantly burning pilot light which is independent of the 15 operation of the main burner and is positioned adjacent thereto, for the purpose of igniting the main burner when gas is admitted to it by means of the thermostatic valve.

Another arrangement which is commonly 20 used is that of having a by-pass around the thermostatic valve which at all times admits a small supply of gas to the main burner which in this case is in operation at all times. The thermostatic valve is used to increase or 25 decrease the flow of gas to the burner in accordance with the temperature of the liquid with which it is in contact.

The first named arrangement which 30 contemplates the use of an independent pilot light usually includes a blue flame gas burner of the atmospheric type in which a certain amount of air is premixed with the gas before combustion takes place. Burners of this 35 type are sometimes referred to as Bunsen burners.

One of the difficulties encountered in the 40 operation of the Bunsen type of burner is that they have a tendency to flash back and burn in the mixing tube when the gas supply to the burner has been cut down below a certain limit. When the burner operates in 45 this manner it produces a dangerous amount of carbon monoxide which may lead to serious results if this poisonous gas escapes from the appliance.

One of the ways in which flashing back of 50 the burner is prevented is by the use of a sheet of gauze between the burner orifices and the mixing tube. This arrangement is not entirely satisfactory due to the fact that the

means present for the ignition of the gas the full flow of unburned gas escapes from the burner. Serious accidents have occurred under such conditions when it has been attempted to relight the burner when the appliance was full of unburned gas. Again under these conditions gas has escaped from the appliance with serious results.

- One of the objects of my invention is to provide a thermostatically controlled gas burner that automatically cuts off the main gas supply to the burner upon extinguishment of the pilot light or reduced main burner flame.
- Another object of my invention is to provide a gas burner control which is operated by a graduating thermostat of a greatly simplified design.

Another object of my invention is to provide an improved gas burner control that efficiently operates with various kinds of gas and at various gas pressures.

Another object of my invention is to provide an automatic and safety control for appliances of the type described in which the gas flow to the main burner is controlled by a single gas valve which is responsive to the temperature of the liquid which is being heated and which is independently responsive in its operation to the pilot burner.

Another object of my invention is to provide a generally improved fuel control which contains a minimum number of parts and a minimum number of adjustments and which is not apt to require adjustments over long periods of operation.

Another object of this invention is to provide a control and burner assembly which forms a single operatively connected unit.

A further object of this invention is to provide a cooperatively associated burner and thermostatic control in which the flow of gas to the burner is controlled by a single valve head which has independent opening means and independent closing means which operate to safely control the flow of gas to the burner.

Another object of this invention is to provide in a control device of the type described, a graduating auxiliary gas valve which effects the opening movement of a snap acting main supply valve.

Another object of this invention is to provide a thermostatic valve with automatic takeup mechanism to automatically maintain the valve in proper adjustment.

Another object of my invention is to provide an improved valve operating snap action mechanism which normally maintains the valve in a closed position.

Another object of my invention is to provide an improved fuel control means which utilizes the thermal energy of a small gas flame to effect the opening and closing movements of the main supply valve.

The present invention includes certain features common to my copending application Serial No. 160,747, filed by me January 12, 1927, and applications 271,798, 271,799, 271,800, 271,801, 271,802, and 271,803, filed by me April 21, 1928, and application Serial No. 3,333, filed January 18, 1925, by L. F. Doen, and application 123,561, filed July 19, 1926, by W. J. Snow, and such common subject matter is hereby disclaimed in the invention to which the present application relates.

In the drawings illustrating a form of my improved control Fig. 1 is a side elevational view partly in section of my improved control adapted for use on an internal fired storage automatic water heater. Fig. 2 is a plan view of the automatic adjustment of the snap action mechanism of my improved thermostatic valve.

The illustration Fig. 1 shows in part an internal fired storage automatic heater of the conventional type. Certain elements of the heater are not shown as they do not form a part and are not necessary for illustrating this invention.

The reference numeral 1 refers to a storage tank having a cylindrical central flue 2 which is adapted to carry off the heated products of combustion from the gas burner 3 and in this manner heat the liquid contents of the storage tank. The storage space of this tank is defined by the inner cylinder 2 and the outer cylinder 1 which are provided with suitable closure heads the lower head 4 being shown. The closure heads are apertured to permit the passage of the heated gases through the flue 2. The tank 1 is surrounded with a suitable insulating material 5 which is secured in place by the outer jacket 6 and is supported by the wall 78 of the combustion chamber containing the burner 3.

The tank 1 is provided with a tapped opening 7 for reception of the thermostat supporting tube 8 which is threaded at one end for reception in tapping 7. The outer end of the tube 8 is threaded for reception in the coupling member 9. The member 9 is threaded for reception of the open end of the thermostat expansion tube 10. The inner end of the thermostat expansion tube which projects into the tank 1 is provided with closure plug 11 that forms an abutment for the thermostat rod 12. The thermostat rod 12 as is the usual practice is made of a material having a materially smaller coefficient of thermal expansion as compared with its cooperating tube 10. The outer end of the rod 12 projects through a central opening 13 formed in the coupling member 9 and contacts the bearing groove 14 which is formed in the compounding lever 15.

The lever 15 acts as a fulcrum lever, its fulcrum bearing 16 being in contact with the adjustable abutment bearing 17. The bear-

ing member 17 is carried in a central opening 18 formed in the adjustment screw 19. The adjustment screw 19 is provided to adjust the position of the bearing pin 17 and in this manner adjust the position of the lever 15. The adjusting screw 19 is threadably received in the T fitting 12 and is provided with a closure cap 21 to prevent the escape of gas therefrom. The T fitting 12 receives at one end the coupling member 9 and is provided with an internally threaded opening 22 for the assembly of the operating elements of the thermostat. The opening 22 is adapted to be closed by a suitable plug if so desired.

The supporting tube 8 of the thermostat has an internal diameter which is somewhat larger than the outer diameter of the thermostat expansion tube 10 allowing free space between these elements which permits liquid from the tank 1 to contact with the entire length of the tube 10. This construction increases the sensitivity of the thermostat by exposing a relatively great length of expansion tube to the liquid by whose temperature it is adapted to be controlled.

The fulcrum lever 15 is housed in a tube 23 which is threadably received in the lower opening of the T fitting 12. The lower end of the tube 23 is provided with a union connection 24 providing a detachable connection with the lower T fitting 25. The side opening 26 of the T fitting 25 is internally threaded for reception of the guide block 27. A second opening 28 in axial alignment with the block 27 is provided with an adjustable cap 29 which provides an abutment for the compression spring 30.

The lower end of the fulcrum lever 15 is forked and has an arcuate cut-out portion 31 for reception of the pin 32. The pin 32 is carried on the outer end of the plunger 33. The spring 30 is compressed between the outer end of the plunger 33 and its adjustment cap 39 and serves to maintain the bearing pin 32 of the plunger in contact with the fulcrum lever 15 at the bearing point 31. In this manner the fulcrum lever 15 is held in contact with the thermostat rod 12 and is constrained to follow the movement of this rod.

The spring 30 by holding the plunger 33 in contact with the lower end of the fulcrum lever 15 causes the plunger to follow the movements of the lower end of the fulcrum lever. The inner end of the plunger 33 has an extending portion 34 which is of smaller diameter than the rest of the plunger and under certain conditions is adapted to contact with the valve head 35. The plunger 33 is accurately fitted in the central bore of the coupling member 27.

The coupling member 27 is provided with an opening 35' which is in communication with the conduit 36 by means of suitable pipe

70 fittings 37'. The plunger 33 cooperates with the opening 35' forming a cylindrical slide valve which is adapted to cover and uncover the opening 35' and permit the flow of gas from the valve body 38 to the conduit 36 and thence to the auxiliary burner 37.

A second burner or ignition pilot 38 is carried in the block 39 and is adapted to be connected by the conduit 75 to the fuel supply line 40 at some point ahead of the thermostatic valve. The burner 38 is adapted to burn at all times during the operation of the appliance and for this reason it is necessary to connect it in the gas supply line ahead of the thermostatic main burner supply valve, 75 which opens and closes in accordance with the movements of the thermostat which is under control of the liquid temperature of the heater.

The lower opening 42 of the T fitting 25 is internally threaded for reception of a suitable closure plug. The valve body 38' is threaded at its inlet end for reception of the gas supply conduit 40 and is threaded at its outlet end for connection to a conventional angle valve 43 having an adjusting needle 44 to control maximum flow of gas to the conduit 45, which is in communication with the burner 3.

The valve body 38 is provided with a valve seat 46 which cooperates with the valve head 35 in the control of gaseous fuel to the burner 3. An extending shoulder or flange 47 is formed on the valve body for the reception and mounting of the valve frame 48 which is held in place by means of the cap screw 49 and the bearing screw 50.

The extension 47 of the valve body 38 is centrally bored at 51 to slidably receive the valve stem 52. The valve stem 52 is connected in any suitable manner such as by a ball and socket joint to the valve head 35. The outer end of the valve stem 52 is provided with a pair of parallel machined faces or flat grooves 53 which are adapted to freely fit in the forked end 54 of the fulcrum or oscillating lever 55.

The upper end of the lever 55 is pivotally mounted at 56 in a suitable extension 57 formed on the valve frame 48. A conical depression or bearing is formed in the extension 58 of the lever 55. A spring abutment 59 having a conical extension is supported in the bearing or depression formed in the boss 58 of the lever 55. A similarly formed spring abutment 60 is carried in like manner in a conical depression formed in the head of the bolt 50. A compression spring 61 is positioned between the spring abutments 59 and 60 and serves to urge the lever 55 to its 110 extreme left hand position as viewed in Fig. 1.

The forked end 54 of the lever 55 is provided with contacting edges 62, adapted to engage the side walls formed on the valve stem 52 by the slots 53 and in this manner 120 125 130

- cause the valve stem and its associated valve head to follow the movements of the lever 55. One end of the toggle link 63 is pivotally mounted at 64 in the lever 55. A pair of adjusting screws 65 are adjustably received 5 in the laterally extending portion 66 which forms a part of the toggle link 63. The adjusting screws 65 are provided for the purpose of limiting the arc of swing of the toggle link 63 about its bearing 64.
- 10 The other end of the toggle link 63 is pivotally connected at 67 to the adjustable toggle link 68. The toggle link 68 is provided with a rectangular opening for reception of the ratchet member 69. Ratchet member 69 is secured by means of a ball and socket joint 70 to the free end of a strip of bimetallic thermostatic metal 71. The ratchet member 69 is provided with a series of notches 72 which cooperates with the flat spring 73 which is secured to the link 68 by means of a screw or rivet 74. By this arrangement any permanent distortion or change in the shape of the thermostatic strip 71 is automatically taken care of and compensated for.
- 15 It will be noted that this automatic adjustment works in one direction and will take up any distortion in the strip 71 which would cause it to swing to the left as viewed in Fig. 1. All of the strains to which the thermostatic member 71 is subjected are in a direction which would tend to cause it to be bent in the direction suggested and in order to keep the valve parts in proper adjustment it is only necessary to provide a take-up for movement 20 of the thermostat metal in the indicated direction.
- 25 With the operating elements of the thermostatic valve in the position shown in Fig. 1, which is the closed position of the valve, upon movement of the thermostatic strip 71 to the right, induced by heat from the burner 37 the toggle links 63 and 68 are moved to the right. This motion is transmitted to the oscillating lever 55 swinging it to the right and causing the compression of the spring 61. When the thermostatic strip 71 has moved the above named elements a certain distance, determined by the relative adjustment the bearing points 70, 67 and 64, the toggle links 25 30 35 40 45 50 55 60 to form a unitary piece of metal which changes its shape with changes in temperature.

In the present instance the thermostatic strip 71, which is held in place against the valve frame 48 by means of the pilot block 39, upon being heated tends to assume the shape of the arc of a circle. Its upper end is in this manner shifted to the right moving the toggle links 63 and 68 and the oscillating lever 55 and associated valve stem 52 and valve head 35 in the manner previously described and opening the valve and admitting a supply of gas to the burner 3. At the instant the valve opens it shifts to its extreme right hand position covering the valve seat 76 which is formed in the member 27. In this manner the supply of gas is temporarily shut off to the burner 37.

20 In a short time the thermostatic strip 71 cools and shifts to the left allowing the valve head under the influence of the spring 77 and associated valve operating parts controlled by spring 61 to follow this movement.

25 This movement of the valve head 35 by the spring 77 causes the valve seat 76 to be uncovered and again placing the conduit 36 in communication with a source of gaseous fuel supply. In this manner gas is re-admitted to burner 37 which in turn is again ignited by the flame of the pilot burner 38 and reheating of the thermostatic strip 71 then takes place.

In the actual operation of the device it has been observed that upon opening of the valve 35 the auxiliary burner 37 is completely extinguished and upon the re-admission of gas thereto this pilot burns with a very small flame which is just sufficient to maintain the valve in open position. When too much gas is admitted to the burner 37 the strip 71 shifts further to the right and cuts down the supply of gas to the burner 37. By this arrangement the thermostatic strip 71 regulates and measures out a proper amount of gas to maintain the valve in open position.

45 When water in the tank 1 has reached a predetermined temperature the thermostatic rod and tube 10 and 12 respectively have shifted to the left. This shifting of the rod 50 and tube 10 and 12 allows the spring 30 to shift the lower end of the fulcrum lever 15 and the associated plunger 33 to the left, covering the port 35 and cutting off the supply of gas to the burner 37. When this event takes place, namely extinguishment of the burner 37, the thermostatic strip 71 cools and allows the compression spring 61 to snap the valve to its closed position in the manner previously described.

55 60 If for any reason the valve operating parts fail to function as intended and the burner 3 is not extinguished at the proper time continued heating of the water will cause the plunger 33 to be shifted still further to the left and upon continued movement of this

element the reduced extension 34 will contact with the valve head 35 and positively move it to its closed position. This action would take place only under abnormal conditions as previously outlined.

70 By this arrangement of a liquid temperature responsive thermostatic valve and a flame responsive thermostatic valve a novel control is provided for heaters of the type described, that positively and safely controls 75 the flow of gaseous fuel in such appliances.

If for any reason the pilot burner 38 should become extinguished there will normally be no means provided to ignite gas emitted from the burner 37 and consequently it will be 80 impossible to turn on the main gas supply to the main burner 3, thus preventing the escape of a dangerous amount of gas therefrom.

85 The independent closure of the valve which is effected by means of the tank thermostat causing the element 34 to engage the valve head 35 when the liquid within the tank exceeds a predetermined temperature provides an independent safety feature which further 90 insures the safe operation of this control.

Another important feature of this control is due to the fact that the thermostatic valve 41, is normally in a closed position. Should breakage of the thermostatic strip 71 occur 95 or failure of the toggle links 63 or 68, the spring 61 would operate to maintain the valve in closed position. In the event of breakage of the spring 61 the spring 77 would serve the same purpose and under almost any conceivable condition the valve would tend to fall in a safe or closed position.

100 Furthermore, it is to be understood that the particular forms of apparatus shown and described, and the particular procedure set forth, are presented for purposes of explanation and illustration and that various modifications of said apparatus and procedure can be made without departing from my invention as defined in the appended claims.

110 I claim:

1. A snap action mechanism comprising, a pivotally supported oscillating lever, resilient means engaging one side of said lever, a toggle link pivoted to said oscillating lever and substantially perpendicular thereto, means to adjust the arc of movement of said link about said lever, a second toggle link pivotally connected to said first named toggle link and actuating means connected to said second toggle link.

115 120 125 130 2. A snap action mechanism comprising, a vertically disposed pivotally supported oscillating lever, spring resisted means in operative engagement therewith, actuating means and a pair of horizontally disposed toggle links pivotally connected to each other interposed between said actuating means and said oscillating lever and operatively connected

therewith and adjusting means provided by one of said toggle links to vary the length thereof.

3. A snap action mechanism comprising, 5 a pivotally supported oscillating lever, spring resisted means in operative engagement therewith, actuating means and a pair of pivotally connected toggle links interposed between said actuating means and said oscillating 10 lever and operatively connected therewith and adjustment take-up means provided by one of said toggle links comprising, a ratchet having teeth formed thereon and means to engage said teeth to vary the length of the 15 said toggle link.

4. A snap action mechanism comprising, an oscillating lever pivotally supported at one of its ends, a pair of pivotally joined toggle links one of which is connected to said 20 oscillating lever substantially perpendicular thereto, operating means connected to the other of said toggle links, means to automatically adjust the length of one of said links, and means to vary the arc of travel of the 25 other of said toggle links about its connection to said oscillating lever.

5. In a valve, a snap action mechanism comprising, an oscillating lever pivotally supported at one of its ends, a pair of pivotally joined toggle links one of which is connected to said oscillating lever substantially perpendicular thereto, resilient means associated with said oscillating lever, operating means connected to the other of said toggle links, 30 and valve means comprising, a valve stem, and valve head operatively associated with said oscillating lever.

6. In a valve, a valve body having a valve port formed therein, an oscillating lever pivotally supported at one of its ends, a pair of pivotally joined toggle links one of which is pivotally connected to said oscillating lever substantially perpendicular thereto, resilient means associated with said oscillating 45 lever, operating means pivotally connected to the other of said toggle links, a valve head, a valve stem connected thereto and operatively associated with said oscillating lever, and a compression spring in contact with said valve 50 head to assist in moving it to its closed position.

7. A liquid heater comprising, a storage container, a gas burner adapted to heat the liquid contents of said container, thermostatic elements responsive to the temperature of the liquid in said container, a fulcrum lever associated therewith and valve means controlled by said fulcrum lever, an auxiliary gas burner under control of said valve means, 55 and a thermostatic valve having an opening in which said valve means are supported, said thermostatic valve being adapted to be moved to open position when a flame is supported by said auxiliary burner.

65 8. A liquid heater comprising, a storage

vessel, a gas burner to heat contents of said storage vessel, a thermostatic valve to control the flow of gas to said burner, an auxiliary burner to supply the energy required for the operation of said thermostatic valve, a compounding lever, thermostatic elements operatively associated with said compounding lever, a sleeve valve comprising a port and a plunger under control of said lever said plunger being adapted to control the flow of gas through said port and to contact with said thermostatic valve to move it to closed position. 70 75

9. A safety control for gas burning appliances comprising, a main heating gas burner, thermostatic means responsive to the temperature of the medium which is being heated, an ignition pilot burner adjacent said main heating burner, an auxiliary burner adjacent said ignition burner, a thermostatic element adjacent said auxiliary burner and adapted to be heated thereby, snap action means connected to said thermostatic element, and valve means controlled by said snap action mechanism and adapted to be controlled by said first named thermostatic means independently of the operation of said auxiliary burner. 80 85 90

10. A safety control for gas burning appliances comprising, a main heating gas burner, thermostatic means responsive to the temperature of the medium which is being heated, an ignition pilot burner adjacent said main heating burner, an auxiliary burner adjacent said ignition burner, a thermostatic element adjacent said auxiliary burner and adapted to be heated thereby, snap action means connected to said thermostatic element, and valve means controlled by said snap action mechanism adapted to be controlled by said first named thermostatic means independently of the operation of said auxiliary burner, said first named thermostatic means being adapted to control the flow of gas to said auxiliary burner. 95 100 105

11. A safety control for gas burning appliances comprising, a main heating gas burner, an ignition pilot burner adjacent said main heating burner, an auxiliary burner adjacent said ignition burner, a thermostatic element adjacent said auxiliary burner and adapted to be heated thereby, snap action means connected to said thermostatic element, valve means controlled by said snap action means, and thermostatic means responsive to the temperature of the liquid being heated and adapted to control the flow of gas to said auxiliary burner and to positively shift said valve means to closed position. 110 115 120

12. A snap action mechanism comprising an oscillating fulcrum lever pivotally supported at one of its ends, a pair of toggle links connected to said fulcrum lever and forming substantially a right angle therewith, resilient means associated with said lever to op- 125 130

pose its movement in one direction and operating means connected to said toggle links, said toggle links being adapted to shift and change the point of application of the force of said operating means on said fulcrum lever upon a predetermined movement of said lever about its bearing.

13. A snap action mechanism comprising a spring resisted oscillating lever, operating means for said lever, and a pair of pivotally joined toggle links connecting said operating means to said oscillating lever forming substantially a right angle therewith and being adapted to vary the point of application of the force of said oscillating means on said oscillating lever upon a predetermined movement of said oscillating lever.

14. A snap action mechanism comprising a fulcrum lever, actuating means therefor, resilient means to continuously oppose the movement of said lever in one direction, and means connecting said actuating means with said lever and bodily movable therewith adapted to vary the mechanical advantage of said lever by quickly shifting the point of application of the force of said actuating means on said lever upon passing through a position of unstable equilibrium and thereby completing the stroke of said lever with a snap movement.

15. A liquid heater comprising, a storage vessel, a main gas burner to heat contents of said storage vessel, a pilot burner therefor, a thermostatic valve to control the flow of gas to said main burner, an auxiliary burner positioned adjacent said pilot burner and said valve to supply the energy required for the operation of said valve, a device controlled by a condition of the liquid in said vessel, and supplemental valve means actuated by said device to control the flow of gas to said auxiliary burner and to engage and move said thermostatic valve to its closed position.

16. A liquid heater comprising, a storage vessel, a main gas burner to heat contents of said storage vessel, a pilot burner therefor, a thermostatic valve to control the flow of gas to said main burner, an auxiliary burner positioned adjacent said pilot burner and said valve to supply the energy required for the operation of said valve, a device controlled by a condition of the liquid in said vessel, and supplemental valve means actuated by said device to control the flow of gas to said auxiliary burner and thereby cause the functioning of said main burner under normal operating conditions and under abnormal operating conditions said device is arranged to cause said valve means to engage and move said thermostatic valve to its closed position.

17. A water heating device comprising, a storage vessel, and a main gas burner for supplying heat thereto in combination with a thermostatic valve located adjacent said

burner and comprising a body having a bypass outlet formed therein, a thermostatic actuating element, valve means in said body operatively connected to said element, an auxiliary gas burner located adjacent said element to supply heat thereto, and means comprising a graduating thermostat in said vessel and an associated compounding lever having a sleeve valve connected thereto and carried in the bypass of said body to control the flow of gas to said auxiliary gas burner.

In testimony whereof I affix my signature.
EDWARD J. TE PAS.
